UNITED STATES PATENT OFFICE.

LOUIS J. HIRT, OF SOMERVILLE, ASSIGNOR TO HENRY W. PEABODY & CO.,
OF BOSTON, MASSACHUSETTS.

FUEL-ECONOMIZER.

SPECIFICATION forming part of Letters Patent No. 518,718, dated April 24, 1894.

Application filed May 9, 1893. Serial No. 473,518. (No model.)

To all whom it may concern:

Be it known that I, LOUIS J. HIRT, of Somerville, county of Middlesex, State of Massachusetts, have invented an Improvement in 5 Fuel-Economizers, of which the following description, in connection with the accompanying drawings, is a specification, like letters and figures on the drawings representing like parts.

10 Fuel economizers as commonly constructed consist of a series of parallel and usually vertical pipes connected at their opposite ends to continuous headers or boxes, and arranged side by side in ranks or rows. The upper 15 header of one rank or row is connected at one end with the upper header of the rank at one side, while the lower header is connected at its opposite end with the adjacent header of the rank at the other side, and so throughout 20 the entire battery, in order that the fluid to be heated shall traverse each rank in turn, heat being supplied by waste products of combustion, or otherwise. In such construction, however, the fluid is apt to take the 25 shortest course and pass from one to the other header of a rank or row through a portion only of the connecting pipes, permitting a large number to remain idle, and utilizing only a portion of the total heating surface of 30 the battery, which results in a much lower degree of heat imparted to the fluid than would be obtained from the entire heating surface.

This invention has for its object the production of an apparatus to overcome the above 35 mentioned objections, and wherein the entire heating surface is utilized, the construction being so arranged that the fluid must come in contact with such surface in its passage through the battery.

40 In accordance therewith my invention consists, in a fuel economizer, of an upper and a lower header, each consisting of a plurality of independent chambers, the chambers of the lower header being rigidly connected combined with a series of pipes connecting the 45 headers and opening into the chambers therein, to form an inlet and outlet for each chamber whereby the fluid to be heated traverses the successive pipes and chambers alternately 50 in its passage through the headers, said lower headers being supported at their ends and

sustaining the pipes and upper headers, substantially as will be described.

Other features of my invention will be hereinafter described and particularly pointed out 55 in the claims.

Figure 1 in side elevation represents a fuel economizer embodying my invention, and partly broken out, the masonry being in section. Fig. 2, is an end elevation thereof, 60 broken out to show the interior arrangement, the masonry being omitted. Fig. 3 is a top view of the apparatus shown in Figs. 1 and 2; and Fig. 4 is a modification to be described.

I have herein shown in Fig. 2, the lower 65 headers *a* as seven in number, the bottom of each inclining from the ends toward the center, as shown in Fig. 1, and divided by partitions *a'* into a series of chambers *b*, see full and dotted lines in Fig. 1, the vertical pipes 70 *c*, *c'* fitting into openings in the tops of said headers, and as herein shown two pipes communicate with each chamber *b*, eight pipes in each rank or row. As herein shown the upper 75 headers are independent chambers or caps *d*, three in number, placed end to end, and connecting the upper ends of two vertical pipes, the lower ends of which are connected with adjacent chambers *b* in the lower header, the pipe *c* of the series, at the left 80 viewing Fig. 1, being connected with the inlet *I*, while the top of the pipe *c'* at the right hand end of the series is connected with the adjacent end pipe *e* of the next rank by a lateral connection *f*. It will thus be seen 85 that the fluid to be heated entering at the inlet *I*, will pass down the end pipe *c* in the direction of the arrow 10, Fig. 1, into the first chamber *b*, thence up through pipe *c'* to cap *d*, down the third pipe *c* into the second chamber *b*, thence up through the fourth pipe *c'*, 90 and so on to the fourth or last chamber *b*, whence it passes up the right-hand end pipe *c'* and through lateral connections *f* to the end pipe *e* of the second rank, the two pipes 95 entering each chamber forming an inlet and outlet therefor. The arrangement of this second rank is like that described of the first rank, the fluid passing up and down through alternate pipes of the series, in this instance, 100 however, from the right-hand end, viewing Fig. 1, to the left, the upper end of the last

pipe e' , see dotted lines Fig. 3, being laterally connected at f' to the adjacent pipe g of the third rank. The fluid circulates in similar manner through every pipe and chamber alternately, throughout each rank until it reaches the end pipe h of the last rank or row and is thence discharged into the outlet O .

While the caps d forming the upper headers are herein shown as independent it is obvious that they may be made as a single casting with independent chambers, if so desired.

The upper ends of the end pipes of adjacent ranks may be rigidly connected in pairs by bolts 5 extended through suitable ears 6 on the pipes, as in Fig. 3, or three or more pipes may be connected as shown in Fig. 2, as may be most convenient.

For convenience in construction, and to permit free expansion, the intermediate pipes of each rank are shown as shorter than the end pipes, the upper headers being close together to economize space and give greater rigidity to the apparatus.

It is sometimes desirable to circulate a greater quantity of the fluid through the apparatus without increasing the diameter of the vertical pipes, and in order to do this the inlet is connected with the end pipes c^x and e^x of two adjacent rows, as in Fig. 4, the fluid passing through the series in parallel currents to the pipes c'^x and e^x at the other end, said pipes being connected by a suitable cap d^x , which is laterally connected at f^x with a similar cap into which the end pipes of the next two ranks open. This arrangement is continued throughout the battery, the two streams or currents uniting at the tops of the end pipes of the two ranks and separating again as they enter the end pipes of the next two rows. Any number of ranks may be so connected, according to the quantity of fluid to be circulated, but whatever the number the entire heating surface of the apparatus is utilized.

In order that the sediment collecting in the lower headers may be conveniently removed, I have provided them with suitable blow-off cocks m , at the lowest point in the bottom thereof, a small opening b^x in the partitions a' permitting the sediment to escape from the different chambers b , said openings, however, not interfering in any way with the circulation of the fluid as herein described.

The ends of the lower headers rest upon suitable masonry or other supports, as shown in Fig. 1, and sustain the apparatus, which may be kept from lateral displacement by suitable braces k , which do not interfere with the expansion or contraction of the apparatus.

I claim—

1. In a fuel economizer, an upper and a lower header, each consisting of a plurality of independent chambers, the chambers of the lower header being rigidly connected,

combined with a series of pipes connecting the headers and opening into the chambers therein to form an inlet and outlet for each chamber, whereby the fluid to be heated traverses the successive pipes and chambers alternately in its passage through the headers, said lower headers being supported at their ends and sustaining the pipes and upper headers, substantially as described. 75

2. In a fuel economizer, an upper and a lower header, each consisting of a plurality of independent chambers, the chambers of the lower header being separated by walls forming a part thereof, combined with a series of pipes connecting the headers and opening into the chambers therein, to form an inlet and outlet for each chamber, and sediment exits in the walls separating the chambers of the lower header, substantially as described. 80

3. In a fuel economizer, an upper and a lower header, each consisting of a plurality of independent chambers, the chambers of the lower header being separated by walls forming a part thereof, combined with a series of pipes connecting the headers and opening into the chambers therein, the bottom of the lower header being inclined continuously from its ends to its center, a blow-off at the lowest point, and sediment exits in the separating walls of the several chambers, of the lower header, substantially as described. 90

4. In a fuel economizer, a series of upper and lower headers arranged side by side respectively, each header consisting of independent chambers, combined with a rank of pipes connecting each upper header with a lower header, and opening into the chambers therein to form inlets and outlets therefor, the intermediate pipes of each rank being shorter than the end pipes, connections between the upper ends of the longer end pipes of a plurality of ranks, and lateral fluid passages between adjacent ranks of connected upward headers whereby the fluid is made to traverse said adjacent ranks in opposite directions, substantially as described. 105

5. In a fuel economizer, a series of lower headers arranged side by side and supported at their ends, an upper header connected to each lower header by a series of pipes, the headers consisting of independent chambers into which the pipes open to form an inlet and outlet for each, combined with independent rigid connections between the upper ends of the end pipes of a plurality of lower headers, and lateral fluid passages between adjacent ends of the upper headers, substantially as described. 115

In testimony whereof I have signed my name to this specification in the presence of two subscribing witnesses.

LOUIS J. HIRT.
